UNITED STATES PATENT OFFICE.

JOHN EDWARD LOCK, OF LAWRENCE, MASSACHUSETTS.

TENPIN APPARATUS.

1,169,045.

Specification of Letters Patent. Patented Jan. 18, 1916.

Application filed July 28, 1915. Serial No. 42,447.

To all whom it may concern:

Be it known that I, JOHN EDWARD LOCK, a subject of Great Britain, now residing at Lawrence, in the county of Essex and State 5 of Massachusetts, have invented certain new and useful Improvements in Tenpin Apparatus; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 This invention relates to new and useful improvements in tenpin apparatus and consists especially in the provision of a tenpin table having a spring-pressed member for firing the balls and comprises a simple 20 and efficient apparatus of this nature having various details of construction, combinations and arrangements of parts which will be hereinafter fully described, shown in the accompanying drawings and then 25 specifically defined in the appended claims.

My invention is illustrated in the accompanying drawings, in which:—

Figure 1 is a side elevation showing the application of my invention to the table. 30 Fig. 2 is a top plan view. Fig. 3 is an enlarged detail end view of the spring-pressed ball shooting device. Fig. 4 is a sectional view on line 4—4 of Fig. 3, and Fig. 5 is a detail in side elevation of the plunger 35 releasing mechanism.

Reference now being had to the details of the drawings by numeral, 1 designates a table mounted upon the table legs 2 which have leg leveling devices 3 at the lower 40 ends thereof. The table has an inclined way 4 about two sides and at one end thereof, and a pocket 4' is positioned at the exit end of said inclined way to catch the balls as they roll down the way.

45 5 designates a netting about a portion of the table upon which the pins 6 are adapted to be placed.

At one end of the table is a slotted plate 7, shown in section in Fig. 4, and 8 designates a hollow boss having a lateral T-shaped projection 9, the end of which is movable within the slotted plate 7. A cylinder, designated by numeral 10, having a closed end with an aperture 11 therein, is mounted upon the post 12 which is journaled within said boss 8, being held

thereon by a nut 13. Said post has a flange 14, and 15 is a screw passing through said flange and a threaded aperture in the cylinder, adapted to hold the latter to the post. 30 Said cylinder is provided with slots 16 in the opposite sides thereof, which slots have offsets 17, one upon one slot being in the lower marginal edge of the marginal wall of the slot, and the other upon the upper 65 side upon the upper wall of the slot.

18 is a ball driving member having a stem 19 which is movable within the aperture 11 in one end of the cylinder, the end portion of which is guided within the aperture 20 formed in the bushing 21, which latter is circumferentially threaded and engages interior threads in the end of the cylinder and which bushing is held in place by a set screw 22. Said stem has an integral collar 70 23 from which pins 24 project in opposite directions and which pins are movable within the slcts 16. A coiled spring 25 is mounted about said stem and bears intermediate the inner end of the bushing 20 and the 80 collar 23.

Pivoted upon a pin 26, projecting outwardly from the boss 8, as shown in Fig. 3 of the drawings, is a link 27 which in turn is pivoted at 28 to a lever 29 on a pivot at right angles to the outwardly projecting pivot before mentioned, said lever having an elongated slot 30, shown clearly in Fig. 1 of the drawings. A plunger releasing member 31 is mounted upon a pin 32 and a spring 33, mounted upon the bracket member 34, serves to hold the lever 31 normally in the position shown in Fig. 5. A pin 35, projecting from the cylinder, serves to limit the throw of the lever in one direction. 95

The operation of my invention will be readily understood and is as follows:—The pins are placed upon the table as shown in Fig. 2 and the ball firing member is drawn back under the tension of the spring 25 through the medium of the lever 29 which is manipulated so that the elongated slot 30 therein will engage over one of the projecting pins 24 when the lever assumes the position shown in dotted lines in Fig. 1, after which, by swinging the lever to the right, the ball firing member or plunger will be moved outward and, when the pins carried thereby come opposite the two offsets in the marginal edges of the slots, a partial axial movement will be imparted to the stem 19 100 105 110

which will cause said pins to engage the offset and hold the plunger retracted under tension of the spring. When the plunger or ball firing member is thus held in readiness to be released, the cylinder carrying the same may be moved freely back and forth through the medium of the sliding connection between the T-shaped projections and the slotted plate 7 and, the post of said cylinder being swiveled, the cylinder may be given a horizontal swinging movement in order to line up the same in readiness to release the ball firing member when in proper alignment with the ball against which it is to be fired. By raising up upon one end of the lever 31, the opposite end, which is positioned over one of said pins 24, will cause the stem of the plunger to move axially a slight distance, sufficient to allow the pins to be released from their offsets and the spring will forcibly drive the member 18 against the ball to be fired against the pins.

It will be noted from the foregoing that means is provided whereby the ball firing member may be held in different positions transversely and allowed also a swinging movement upon the pivot, so that the ball may be driven in any direction desired.

What I claim to be new is:—

- 30 1. A tenpin ball firing apparatus, comprising a table, a slotted plate fastened to the latter, a pivotal cylinder and mounting therefor movable within said plate, a spring-pressed member within the cylinder, the latter having slots with offsets at the ends thereof, projections upon said member which are in alignment with said offsets to hold the member retracted, and a trigger mechanism for releasing the latter.
- 40 2. A tenpin firing apparatus, comprising a table, a slotted plate fastened to the latter, a pivotal cylinder and mounting therefor movable within said plate, a spring-pressed member within the cylinder, the latter having slots with offsets at the ends thereof, projections upon said member which are in alignment with said offsets to hold the member retracted, a pivotal spring-pressed lever

adapted to impart an axial movement to said member to release the pins from the slots. 50

3. A tenpin firing apparatus, comprising a table, a slotted plate fastened to the latter, a hollow boss having a T-shaped projection movable within said plate, a cylinder, a post connected thereto and swiveled in said boss, 55 a ball firing member having a stem movable through an apertured end of said cylinder, a hollow threaded member within said cylinder and through which said stem is guided, a collar upon said stem, a spring interposed 60 between said member and collar, said cylinder having oppositely disposed slots terminating in offsets, pins upon said collar and movable through said slots and adapted to engage said offsets, and a spring-pressed lever adapted to engage one of said pins to 65 impart a rotating movement to the stem to release the pins from said offsets.

4. A tenpin apparatus, comprising a table, a slotted plate at one end of the table, a hollow boss with an integral T-shaped projection movable within the slot of said plate, a cylinder, a post fastened thereto pivotally mounted in said boss, said cylinder having an apertured end and longitudinal slots in the wall thereof, a ball firing member, a stem thereto movable through apertured end of the cylinder, a collar upon said stem with pins projecting therefrom and guided in said slots, the latter having offsets for the 70 reception of the pins, a hollow threaded member in one end of the cylinder within which the stem is guided, a spring interposed between said threaded member and collar, and a spring-pressed lever mounted 75 upon the collar and adapted to contact with one of said pins to impart a rotating movement to the stem and allow the spring to act 80 to drive the ball actuating member. 85

In testimony whereof I hereunto affix my 90 signature in presence of two witnesses.

JOHN EDWARD LOCK.
